CLAIM

The ornamental design for a bicycle bucket, as shown and described.

DESCRIPTION

The present application is related to U.S. patent application Ser. No. 12/564,503, filed Sep. 22, 2009 entitled Systems and Methods for Providing a Bicycle with Large Load Carrying Capacity.

FIG. 1 is a perspective view of the bicycle bucket as used on a representative bicycle;

FIG. 2 is a left side view of the bucket as used on a representative bicycle;

FIG. 3 is a right side view of the bucket as used on a representative bicycle;

FIG. 4 is a rear view of the bucket as used on a representative bicycle;

FIG. 5 is a rear view of the bucket as used on a representative bicycle;

FIG. 6 is a top plan view of the bucket as used on a representative bicycle; and,

FIG. 7 is a top plan view of the bucket as used on a representative bicycle.

The broken lines showing the bicycle illustrate environmental structure and form no part of the claimed design.
